UNITED STATES PATENT OFFICE

153,913

DESIGN FOR A DISHWASHING MACHINE

Thomas Stephen Bartlett, London, Ontario,
CanadaApplication January 29, 1949, Serial No. 571
In Canada August 6, 1948

Term of patent 14 years

(Cl. D49—1)

To all whom it may concern:

Be it known that Thomas S. Bartlett, a subject of the King of Great Britain and resident of the city of London, county of Middlesex, Province of Ontario, in the Dominion of Canada, has invented a new, original, and ornamental Design for a Dishwashing Machine, of which the following is a specification, reference being had to the accompanying drawing, forming part thereof.

The drawing represents a perspective view of a dishwashing machine embodying my new design, the side and back not shown being plain, similar to the side illustrated.

I claim:

The ornamental design for a dishwashing machine, as shown and described.

THOMAS STEPHEN BARTLETT.
